UNITED STATES PATENT OFFICE.

HAKULYO CHUHACHI TANABE, OF MARYSVILLE, CALIFORNIA, ASSIGNOR OF ONE-
THIRD TO KINJIRO SASAKI, OF MARYSVILLE, CALIFORNIA.

WINDOW-SEAT.

1,280,581.

Specification of Letters Patent.

Patented Oct. 1, 1918.

Application filed November 3, 1917. Serial No. 200,130.

To all whom it may concern:

Be it known that I, HAKULYO CHUHACHI TANABE, a citizen of the Japanese Empire, residing at Marysville, in the county of

5 Yuba and State of California, have invented new and useful Improvements in Window-Seats, of which the following is a specification.

This invention relates to a window seat 10 which is capable of being removably secured to the outside of a window and aims to provide a device which may be quickly and easily converted into a rocking chair.

The primary object of the invention is to 15 provide an article, capable of the above set forth uses, which may be easily and quickly folded into a compact form when not in use.

The invention also comprehends the novel 20 form of supporting means pivoted to the platform which supports a seat, the supporting means being adapted for contact beneath the window and being capable of having its contacting end removably secured to the front of the platform, whereby the supporting means will serve as rockers.

The invention also provides novel means of adjusting the supporting means to adjust the window seat into horizontal position, which means consists of a flexible element 25 carried by the supporting means and adjustably engaging the platform.

The invention further comprehends a novel form of seat support which is pivotally secured to the standard carried by the platform, the seat support consisting of a U-shaped frame engageable with the front end of the seat.

The invention further consists of the following novel details of construction and arrangement of parts, hereinafter more fully described and illustrated in the accompanying drawings, in which—

Figure 1 is a perspective view of the invention in use as a window seat;

Fig. 2 is a similar view showing the same detached from engagement with the window;

Fig. 3 is a perspective view of the invention in use as a rocking chair; and

Fig. 4 is a side elevation showing the same folded.

Referring in detail to the drawings, the numeral 10 designates a pair of parallel side bars, preferably formed of angle iron.

55 These side bars are connected together by transverse slats 11, so as to form a platform

which supports the various parts of the combined chair and seat and by means of which the seat may be supported adjacent to the window casing.

60 Pivots secured to one end of the platform by means of a rod 12 which passes through the side bars 10, is a pair of standards 13. These standards are spaced apart by an end bar 14 and an intermediate bar 15, the standards being further braced by cross-bars 16, one end of each of these bars being pivotally mounted upon the rod 12, while their opposite ends are secured to the standards 13. The ends of the standards 70 13 which are pivoted to the side bars 10 are curved as shown at 17, so as to space the said standards from said side bars when the device is folded, as will be seen by reference to Fig. 4 of the drawings.

75 Pivots secured to the side bars 10 as shown at 18, are a pair of diagonally arranged braces 19, the upper bars of which are curved at the upper end as shown at 20 and pivotally mounted upon the rod 14. 80 The bars forming the braces 19 are offset as shown at 21 and are further provided at this offset point with a pivot joint 22, so as to enable the two sections of which each of the braces is formed to be folded together when 85 the invention is in the position shown in Fig. 4. In order to limit the movement of the sections of the braces 19 in the direction opposite that shown in Fig. 4, the upper section of each of the braces has secured 90 thereto a stop member 23, consisting of a U-shaped element rigidly secured to the said upper section and adapted to receive the upper end of the lower section when the parts are in the position shown in Figs. 1, 2 and 3. 95

The offset portion 21 of the bars 19 forms a space for the reception of the seat 24. This seat comprises a pair of side bars 25, each having one of their ends pivotally mounted upon the rod 15, these side bars 25 100 being connected by means of slats 26, which together with the bars 25 form the seat 24. The end of the seat opposite that which is pivotally mounted upon the rod 15 is supported by means of a U-shaped member 27, the width of this member being such as to permit it to receive the seat 24, the base of the U engaging the under side of the seat. The opposite end of this U-shaped member is pivotally mounted upon the rod 14, so that by slightly 110 elevating the forward end of the seat 24, the member 27 may be disengaged from the

seat and folded upon the back of the standards 13 as shown in Fig. 4 of the drawings.

The ends of the side bars 10 opposite that to which the standards 13 are secured, are formed with right angular extensions 28, which are substantially U-shaped in cross-section and which have pivotally mounted thereon upon the pivot 29 hooks 30, these hooks being adapted to engage over the inner side of the sill of the window casing. By pivoting the hooks in the manner shown they are capable of being folded up beneath the side bars 10 when not in use and are held in such folded position by means of hooks or chains 31 carried by the side bars 10. Secured beneath the side bars 10 at the angular connection of the extensions 28 therewith are rubber or other buffers 32, so that the said bars will not mar the finish of the window sill.

Pivottally mounted upon each end of the rod 12 is one of a pair of rockers 33, these rockers being formed with extensions 34 which provide short legs for the rear end of the chair. The rockers 33 are curved and carry near their opposite ends short legs 35, which are designed to be removably secured beneath the side bars 10 by means of bolts 36. The front extremities of the rockers 33 are connected by means of the rod 37, these extremities being formed to have removably positioned thereon as shown at 38 and 39, a bar 40. This bar is designed for engagement with the wall of the building below the window, when the device is in use as a window seat.

In order to adjust the seat to a horizontal position when it is connected to the window, the rod 37 has secured thereto a flexible element 41, in the form of a chain, one end of which is engageable with a hook 43 carried by a rod 44 mounted beneath the front slat 11 and forming a pivot by means of which the side bars 10 are connected to the bars 19.

Removably secured upon the rods 14 and 15, through the medium of fastening devices 45 and 46 respectively is a back 47, which is designed for use when the invention is converted into a rocking chair.

It is believed that from the foregoing description, when read in connection with the accompanying drawings, the operation and advantages of the invention will be apparent. The right is reserved to make such changes in the form and proportion thereof as will fall within the scope of the claims hereto appended.

Having described the invention, what is claimed is:—

1. A combined rocking chair and window seat embodying a platform, a seat arranged above said platform, means carried by one

end of the platform for engagement with the window casing, curved bars carried by the opposite end of said platform for engagement beneath the window to support said platform and means whereby the curved bars may be connected to the platform to form rockers.

2. A combined rocking chair and window seat embodying a platform, a seat arranged above said platform, means carried by one end of the platform for engagement with the window casing, a supporting frame secured to said platform, said frame comprising a pair of curved crossed bars having one of their ends pivotally secured to the platform and their opposite ends connected by a bar and means whereby the supporting frame may be connected to the platform to form rockers.

3. A combined rocking chair and window seat embodying a platform, a seat arranged above said platform, means carried by one end of the platform for engagement with the window casing, curved bars carried by the opposite end of said platform for engagement beneath the window to support said platform, means whereby the curved bars may be connected to the platform to form rockers and a flexible element carried by the supporting means and engageable with the platform to adjust it to a horizontal position.

4. A combined rocking chair and window seat embodying a platform, means for securing said platform to a window casing, combined rockers and platform supporting means carried by the platform, a seat pivotally supported above said platform and means pivoted to the seat supporting means and engageable with said seat for holding the latter in position.

5. A combined rocking chair and window seat embodying a platform, means for securing said platform to a window casing, combined rockers and platform supporting means carried by said platform, a seat pivotally supported above said platform and a U-shaped frame pivoted to the seat supporting means and engageable with said seat for holding the latter in position.

6. A combined rocking chair and window seat embodying a platform, means for securing said platform to a window casing, curved bars pivotally secured to the opposite end of said platform and adapted to be removably secured adjacent the opposite end of the platform to form rockers, standards also pivotally secured to the platform, a seat pivotally secured to said standards and foldable side bars pivotally connecting said standards and said platform.

In testimony whereof I affix my signature.

HAKUYO CHUHACHI TANABE.
